UNITED STATES PATENT OFFICE.

DAVID C. EVEREST, OF WAUSAU, WISCONSIN, ASSIGNOR TO MARATHON PAPER MILLS COMPANY, OF WAUSAU, WISCONSIN.

DESIGN FOR WRAPPING-PAPER.

40,992.

Specification for Design.

Patented Nov. 15, 1910.

Application filed July 14, 1910. Serial No. 572,035. Term of patent 7 years.

To all whom it may concern:

Be it known that I, DAVID C. EVEREST, a citizen of the United States, residing at the city of Wausau, county of Marathon, State of Wisconsin, have invented a new, original, and ornamental Design for Wrapping-Paper.

My new, original and ornamental design for wrapping paper is clearly illustrated in the accompanying drawing which is a plan view of a portion of a sheet.

I claim:

The ornamental design for wrapping paper, as shown.

DAVID C. EVEREST.
